UNITARY PUNCHING AND BINDING MACHINE

Robert H. Crowle, 2100 Dempster St., Berwyn, Ill., and
Charles E. Jones, 2100 Dempster St., Evanston, Ill.

Filed Apr. 11, 1960, Ser. No. 60,136

Term of patent 14 years

(Cl. D55—1)

Fig. 1

Fig. 2

Fig. 3

Fig. 4

Fig. 5

Fig. 6

FIGURE 1 is a perspective of a unitary punching and binding machine embodying our new design as viewed from the top-left.

FIG. 2 is a top view of the machine shown in FIG. 1.

FIG. 3 is a front elevational view thereof.

FIG. 4 is a right side elevational view thereof.

FIG. 5 is a rear elevational view of the machine.

FIG. 6 is a fragmentary sectional view of the front cover plate of the machine taken substantially on line 6-6 in FIG. 3.

We claim:

The ornamental design for a unitary punching and binding machine, as shown.
